CLAIM

The ornamental design for a charging unit for a health condition monitoring system as shown and described.

DESCRIPTION

FIG. 1 is an isometric view of an embodiment of the charging unit for a health condition monitoring system; FIG. 2 is a left side view thereof. The right side view thereof being a mirror image of the left side view; FIG. 3 is a top view thereof; FIG. 4 is a front view thereof. The rear view thereof being a mirror image of the front view; and, FIG. 5 is a bottom view thereof.

1 Claim, 1 Drawing Sheet
